ASH TRAY

Edna Verlod, Alameda, Calif.

Application August 26, 1949, Serial No. 4,706

Term of patent 7 years

(Cl. D85—2)

To all whom it may concern:

Be it known that I, Edna Verlod, a citizen of the United States of America, residing at Alameda, county of Alameda, and State of California, have invented a new, original, and ornamental Design for an Ash Tray, of which the following is a specification, reference being had to the accompanying drawing, forming a part thereof wherein:

I claim:

The ornamental design for an ash tray, as shown.

EDNA VERLOD.
